US00D576597S

(12) **United States Design Patent**
Lim et al.

(10) **Patent No.:** US D576,597 S
(45) **Date of Patent:** ** Sep. 9, 2008

(54) **MOBILE PHONE**

(75) Inventors: **Ji-Hyoun Lim**, Seoul (KR); **Seung-Min Park**, Seoul (KR); **Chang-Hwan Hwang**, Goyang-si (KR)

(73) Assignee: **Samsung Electronics Co., Ltd.**, Suwon-Si (KR)

(**) Term: **14 Years**

(21) Appl. No.: **29/290,484**

(22) Filed: **Dec. 10, 2007**

(30) **Foreign Application Priority Data**

Oct. 26, 2007 (KR) 30-2007-0044746

(51) **LOC (8) Cl.** 14-03

(52) **U.S. Cl.** D14/138

(58) **Field of Classification Search** D14/138, D14/496, 341-347; 455/575.3, 575.1
See application file for complete search history.
